CLAIM

The ornamental design for a display rack, as shown and described.

DESCRIPTION

FIG. 1 is a right front perspective view of a display rack showing our new design;

FIG. 2 is a front elevational view, the rear elevational view being a mirror image thereof;

FIG. 3 is a right side view thereof; and,

FIG. 4 is a left side view thereof.

The dashed lines represent environmental elements only, such as signage and various optional shelving units, and form no part of the claimed design.

1 Claim, 4 Drawing Sheets
